(57) CLAIM

The ornamental design for an entertainment venue with track, as shown and described.

DESCRIPTION

FIG. 1 is a front-perspective view of an entertainment venue with track in accordance with the design;
 FIG. 2 is a front-elevation view thereof;
 FIG. 3 is a rear-elevation view thereof;
 FIG. 4 is a right-side view thereof;
 FIG. 5 is a left-side view thereof; and,
 FIG. 6 is a top-plan view thereof.

Any broken lines present in the drawings are for illustrative purposes only and form no part of the design to be patented.
